UNITED STATES PATENT OFFICE.

WILLIAM REDFORD MULOCK, OF WINNIPEG, MANITOBA, CANADA.

PLATEN FOR TYPE-WRITING MACHINES.

1,156,614.

Specification of Letters Patent.

Patented Oct. 12, 1915.

Application filed June 29, 1915. Serial No. 37,066.

To all whom it may concern:

Be it known that I, WILLIAM REDFORD MULOCK, a subject of the King of Great Britain, residing at Winnipeg, in the Province of Manitoba, Canada, have invented 5 certain new and useful Improvements in Platens for Type-Writing Machines, of which the following is a full, clear, and exact specification.

This invention relates to platens for type-writing machines and has for its object to reduce the noise incident to the type striking the platens.

Two elements have been found to contribute principally to producing the noise of the ordinary typewriting machine. One is the hardness of the platens and the other the size of said platens. Lack of resiliency also is responsible to a considerable degree, 20 although this is to a certain extent included in the first element mentioned, namely, the hardness of the platens.

The present invention is based upon the hypothesis that if the type should strike the 25 end of a thin rod of soft metal suspended in the air instead of a large platen, the vulcanized surface of which is hard and resonant, the noise would be reduced almost to the point of imperceptibility, and the aim 30 of the invention is to produce a structure which will carry out this theory in a practical manner.

The invention will be first hereinafter described in connection with the accompanying 35 drawings, which constitute a part of this specification, and then more specifically defined in the claims at the end of the description.

In the accompanying drawings, wherein 40 similar reference characters are used to designate corresponding parts throughout the several views:—Figure 1 is a broken side elevation of a cylinder platen constructed substantially in accordance with this invention, one end portion having a different arrangement of embedded pins or rods from the other end portion. Fig. 2 is an end view 45 of the same. Fig. 3 is an enlarged section taken on the line III—III of Fig. 5, a portion also being shown in end elevation in order to disclose the nuts on the ends of the 50 retaining rods. Fig. 4 is a broken section taken on the line IV—IV of Fig. 3, to more clearly illustrate the retaining rods and the 55 nuts on their ends. Fig. 5 is an enlarged diagrammatic view showing the arrange-

ment of the five-branch and four-branch pins on the surface of the platen. Figs. 6 and 7 are detailed perspective views of the five-branch and four-branch pins. Fig. 8 is an 60 end view of a flat surfaced platen embodying my improvements. Fig. 9 is a broken front elevation of the device shown in Fig. 8, and Fig. 10 is a detailed perspective view of a single pin which may be used instead 65 of the multiple-branch pins, if desired.

Referring first to Figs. 1 to 7, inclusive, the cylinder platen 1 is provided with a surface layer of soft rubber 2 in which small metal pins are embedded with their outer 70 ends flush with the surface of said soft rubber layer. The pins are preferably made of soft metal or other material or substance just hard enough to allow a clear impression of the type being made on the paper. These 75 pins are placed near enough together to insure every type striking one or more of them. For instance, the letter "o" is indicated in dotted lines in Fig. 5 as striking four of the pins. The diameter of the pins, 80 while being quite small, is sufficient to prevent mutilating the paper, especially in view of the close proximity of said pins to one another.

The pins are preferably formed four or 85 five on a single stem, as shown in Figs. 6 and 7, and these groups of four and five pins to a stem are arranged alternately in horizontal and vertical rows, as illustrated in Figs. 1, 3 and 5, so as to space the individual pins equidistant apart. The five pins mounted on a single stem are designated 3 in the drawings and the stem on which they are mounted is indicated at 4. The four pins on a stem are designated 5 and their 90 stems 6. As illustrated in Fig. 1, the surface of the platen may be entirely covered with the pins, as the right hand end of the cylinder, or said pins may be arranged in spaced longitudinal series, as shown on the 95 left hand end of the cylinder. In the latter case, the spacing of the series of pins is according to the usual spacing of the lines of typewriting so that there will always be a series or row of the pins below where the 100 type strike.

The stems 4 and 6 of the pins are provided with plates secured thereto in transverse relation and made of hard rubber or other suitable substance. These plates 110 7 are arranged between pairs of longitudinal rods 8 and 9 which extend through and project

from the ends of the soft rubber surface layer 2. Each pair of rods 8 is arranged on the outer face of one of the plates 7, one of said rods being at either side of the stem of the pins, while each pair of rods 9 is similarly arranged on the inner face of one of said plates. All of the rods are fitted with nuts 10 on their ends, so that they can be removed for repair purposes, etc.

10 Resiliency will be caused by the plates on the pins resting on the longitudinal rods or wires 8 and 9, all of which are embedded in the soft rubber layer, and this construction will also greatly lessen the noise resulting from the type striking the platen or paper placed over it. When the pins are struck by the type, said pins and their transverse plates are thrown inward toward the center of the platen against the pairs of rods or wires 9 and also against the soft rubber in which these parts are embedded. Said pins will, therefore, rebound to their original position where they will be held and maintained by the pairs of rods or wires 8 and the rubber which fills all the interstices between the pins, plates and rods, so that the ends of the pins will not project from the face of the platen. The soft rubber surface layer 2 is, of course, thicker than the pins are long, as shown in Fig. 3, and will present a practically smooth surface.

15 It is not necessary to apply my improvement to a cylinder platen. It may also be used on a flat surfaced platen or case, as illustrated in Figs. 8 and 9, the platen in this instance having a layer 20 of soft rubber in which pins 30 and 50 are embedded in the same manner as already described in connection with the cylinder platen, and in 20 which they are retained by longitudinal rods or wires 80 and 90 similar to the rods or wires 8 and 9. When the flat platen 11 is used, a pair of rollers 12 may be employed for guiding the paper 13 up over its surface.

25 While multiple-branch pins are preferred, as hereinbefore stated, it is obvious that the pins may be made singly, as at 40 in Fig. 10, each of said pins being provided with a 30 transverse plate 70 corresponding to the plates 7 of the pins 4 and 6 for engagement with the wires or rods 8 and 9 in the same manner as illustrated in Figs. 3 and 4. The construction will be the same with the single pins 70 except that there will be more of them than of the multiple-branch pins.

35 Having thus described my invention, what I claim as new and desire to secure by Letters Patent of the United States is:—

40 1. A platen for typewriting machines, the platen having a surface layer of a resilient substance, and spaced pieces of harder material embedded in said surface layer with their outer faces flush with the outer surface 45 of said layer.

2. A platen for typewriting machines, the platen having a surface layer of a resilient substance, and spaced pins made of a harder material and embedded in said surface layer with their ends flush with the outer surface 70 thereof.

3. A platen having a surface layer of a resilient substance, and spaced metal pins embedded in said surface layer with their ends flush with the outer face thereof. 75

4. A platen having a surface layer of a resilient substance, and spaced pins made of harder material and embedded in said surface layer, said pins being disposed substantially at right angles to the outer face 80 of said surface layer and having their outer ends flush with such outer face.

5. A platen for typewriting machines, the platen having a surface layer of a resilient substance, and spaced pieces of harder material embedded in said surface layer with their outer faces flush with the outer surface 85 of said layer, the size and spacing of said pieces being such that each type of the machine will necessarily strike at least one of 90 said pieces.

6. A platen having a surface layer of resilient substance, pins embedded in said substance and arranged substantially at right angles to the outer face of said surface layer, 95 and means for preventing said pins from being driven farther into said substance under impact upon the outer face of said outer layer.

7. A platen having a surface layer of resilient substance, pins embedded in said substance and arranged substantially at right angles to the outer face of said surface layer, and transverse plates on said pins also embedded in said substance for the purpose 105 specified.

8. A platen having a surface layer of resilient substance, pins embedded in said substance and arranged substantially at right angles to the outer face of said surface layer, transverse plates on said pins also embedded in said substance, and reinforcing means in said substance at either side of said plates for the purpose specified. 110

9. A platen having a surface layer of resilient substance, pins embedded in said substance and having their ends flush with the outer face of said surface layer, transverse plates on said pins also embedded in said substance, and longitudinal rods in said substance on the inner side of said plates, for preventing the pins from being driven farther into said surface layer under the impact upon the outer face thereof. 115

10. A platen having a surface layer of resilient substance, pins embedded in said substance and having their ends flush with the outer surface of said substance, transverse plates on said pins also embedded in said surface layer, and longitudinal rods in said 120 surface layer, and longitudinal rods in said 125 surface layer.

substance on the outer and inner faces of the plates for the purpose specified.

11. A platen having a surface layer of resilient substance, pins embedded in said substance and having their ends flush with the outer surface of said substance, transverse plates on said pins also embedded in said surface layer, and longitudinal rods in said substance and arranged in pairs, one pair on the inner side and the other pair on the outer side of said plates, the rods of each pair being arranged one at either side of the pins.

12. A platen having a surface layer of resilient substance, pins embedded in said substance and having their ends flush with the outer surface of said substance, transverse plates on said pins and also embedded in said surface layer, and longitudinal rods overlapping said plates and projecting from the ends of the surface layer.

13. A platen having a surface layer of resilient substance, pins embedded in said substance and having their ends flush with the outer surface of said surface layer, transverse plates on said pins also embedded in said surface layer, longitudinal rods extending through said substance and overlapping

said plates, for the purpose specified, the ends of said rods being threaded and projecting from the ends of the surface layer, and nuts on the ends of said rods.

14. A platen having a surface layer of resilient substance, and pins embedded in said substance, said pins being arranged in groups mounted on common stems.

15. A platen having a surface layer of resilient substance, and devices of harder material embedded in said substance, said devices comprising each a stem and a plurality of branching pins, the latter having their ends flush with the outer face of the surface layer.

16. A platen having a surface layer of resilient substance, and devices of harder material embedded in said substance, said devices comprising each a stem and a plurality of pins branching from said stem, said pins being flush with the outer face of the surface layer and arranged equidistant apart in rows, stems with four and five pins alternating in said rows.

In testimony whereof I have signed my name to this specification:

WILLIAM REDFORD MULOCK.
